(57) **CLAIM**

The ornamental design for a double sided toothed zip tie, as shown and described.

DESCRIPTION

FIG. 1 is a rear, top perspective view of the double sided toothed zip tie, showing my new design;

FIG. 2 is a front, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is a sectional perspective view of 11-11 along the line in FIG. 6;

FIG. 12 is a sectional perspective view of 12-12 along the line in FIG. 6;

FIG. 13 is an enlarged view of detail 13 in FIG. 8;

FIG. 14 is an enlarged view of detail 14 in FIG. 11; and,

FIG. 15 is an enlarged view of detail 15 in FIG. 12.

The dotted lines are indicative of indeterminate length and form no part of the claimed design.

The dash-dot-dash broken lines are for notating enlarged views and form no part of the claimed design.

The dashed broken lines illustrate the location from which the section drawings are created and shown in FIGS. 11 & 12. The dashed broken lines form no part of the claimed design.

1 Claim, 15 Drawing Sheets
